WATER CLOSET VALVE ACTUATING LINKAGE
Andrew D. McFarlane, 2514 Bay City Road, Apt. 13,
Midland, Mich.

Filed July 1, 1959, Ser. No. 824,346
4 Claims. (Cl. 4—67)

This invention relates to water closets and more particularly to an actuating mechanism of improved construction for operating the valve by means of which water is permitted to drain from the tank.

Water closets of the kind in general usage comprises a tank in which water is adapted to be contained until such time as a toilet with which the closet is associated is flushed. At this time a valve normally seated at an opening at the bottom of the tank is lifted by an actuating mechanism so as to permit water in the tank to drain into the toilet. In nearly all of the water closets adapted for residential use, the valve lifting mechanism is controlled by an operating handle which extends through a wall of the tank so as to be manipulated from outside the tank. The mechanism on the inside of the tank usually comprises a lever arm connected to the operating handle in such manner as to be rockable. The lever usually is provided with some means, such as a loop or the like, which is adapted to receive an upstanding stem connected to the valve so that rocking of the lever in one direction will lift the valve off its seat.

In water closets of the kind under consideration, the operating handle should be mounted at a height on the tank which is above the normal water level in the tank so as to avoid any possibility of leakage around the opening which accommodates the handle. The lever thus is mounted at a substantial distance above the bottom of the tank. In conventional constructions, the lever extends more or less horizontally towards the valve stem to the point where it terminates in the loop or other stem receiving part. This construction, however, requires the valve stem to be exceptionally long and in many cases the valve stem is composed of two parts, that is, a pair of links connected one to another. Such a construction is undesirable for several reasons, one of which is that the extra length of the valve stem requires the provision of multiple guides in an effort to secure truly vertical movement of the valve so as to be sure that it will seat properly. Another defect of the known constructions is that the making of the valve stem in multiple parts frequently results in the stem parts binding on one another in such manner as to effect an over-all shortening of the stem, with the result that the valve will not seat properly.

An object of this invention is to provide a water closet valve actuating linkage which overcomes the disadvantages of known constructions.

Another object of the invention is to provide a linkage of the kind referred to which is so related to the stem of the valve that the stem length may be kept to a minimum.

A further object of the invention is to provide a linkage of the kind described wherein the valve lifting part functions as a guide for the valve during movements of the latter.

A further object of the invention is to provide a linkage for actuating a toilet flush valve which is simple and economical in construction and yet which assures positive seating of the valve.

Other objects and advantages of the invention will be pointed out specifically or will become apparent from the following description when it is considered in conjunction with the appended claims and the accompanying drawing, in which:

2

FIGURE 1 is a fragmentary view partly in front elevation and partly in section, disclosing apparatus constructed in accordance with the invention and assembled with conventional water closet parts;

5 FIGURE 2 is a fragmentary, enlarged detail of a portion of the structure shown in FIGURE 1;

FIGURE 3 is a top plan view of the apparatus shown in FIGURE 2; and

10 FIGURE 4 is a sectional view taken on the line 4—4 of FIGURE 2.

Apparatus constructed in accordance with the invention is adapted for use in conjunction with a conventional water closet or tank 1 having front and rear walls 2 and 3, respectively, spaced apart by side walls 4 and a bottom 5. The bottom is provided with an opening in which is received a pipe 6 leading from the tank 1 to a toilet bowl (not shown) in the conventional manner. The opening in the bottom of the tank normally is closed by a hollow ball valve 7 of conventional construction 20 having a vertically extending valve stem 8 secured thereto and projecting a substantial distance above the valve 7. It is customary to provide a guide ring 9 through which the valve stem slidably extends, the ring being supported by an arm 10 which may be mounted in any suitable manner on a part of the tank structure.

The front wall 2 of the tank 1 may have an opening therein through which extends a hub portion 11 of an operating handle 12. In order to prevent the possibility of leakage of water through the opening that accommodates the handle portion, the opening should be so located as to be above the normal level of water in the tank.

35 A valve actuating linkage formed in accordance with the invention is designated generally by the reference character 13 and comprises a lever arm 14 fixed at one end to the operating handle 12 so as to be rockable with the latter about the axis of the hub 11. In the illustrative embodiment of the invention, the other end of the lever 14 telescopingly receives an operating member 15 which is composed of a sleeve part 16 having an opening therein of such size as snugly, but slidably, to receive the end of the lever 14 and be adjustable relatively thereto. Both ends of the sleeve preferably are open so that the member 15 may be located at any desired place on the lever 14. The sleeve part 16 is shown as being split as at 17, but it may form a closed loop if desired.

40 Rigidly connected to the sleeve part 16 is an actuating part 18 which is so located relatively to the sleeve 16 as to make with the latter a right angle. The free end of the part 18 is provided with an opening 19 which is of such size as slidably to receive the valve stem 8. As is perhaps best shown in FIGURE 4, the upper end of the valve stem is enlarged as at 20 to prevent passage of the valve stem completely through the operating part 18.

45 To condition the apparatus for operation, the operating member 15 is placed on the lever arm 14 and adjusted relatively to the latter so as to be located at a position where the opening 19 is aligned with the valve stem 8. The apparatus 15 may be secured in the appropriate position on the lever 14 by means of a set screw 21. Alternatively, any other known and convenient securing means may be used.

50 When the apparatus is conditioned for use, the valve 7 will be on its seat at the opening in the bottom of the tank and the tank will contain its normal supply of water. The operating part 18 will be located slightly below the enlargement 20 at the upper end of the valve stem 8 and it will be noted from FIGURES 1 and 2 that, although the lever 14 and the sleeve 16 are inclined

to the horizontal, the operating part 18 lies in a substantially horizontal plane. The purpose of this construction will be pointed out subsequently.

When it is desired to drain the contents of the tank, the handle 12 is rocked counterclockwise so as to impart corresponding movement to the lever arm 14. The operating part 18 will engage the enlarged upper end 20 of the valve stem 8 and lift the valve 7 off of its seat and thereafter rise rapidly in a conventional manner. As soon as the valve 7 has been raised from its seat, the handle 12 may be released, whereupon the weight of the lever 14 will return the handle 12 and the lever to their normal positions. This will restore the operating part 18 to its generally horizontal position. As the water flows through the drain pipe 6, the valve 7 will move downwardly and it will be guided in its downward movement both by the guide ring 9 and the opening in the operating member 18. When all the water has run out of the tank 1, the valve 7 then will drop on its seat to close the opening. Positive alignment of the valve 7 and its seat will be assured by the cooperative guiding of the ring 9 and the member 18, and the ability of the part 18 to lie in a horizontal plane enables the opening 19 to be only slightly larger than the diameter of the rod 8, thereby promoting proper guidance of the valve.

Although it is preferable to form the lever 14 and the actuating member 15 in separate parts, they may be integrally formed if desired.

The disclosed embodiment is representative of a presently preferred form of the invention, but is intended to be illustrative rather than definitive thereof. The invention is defined in the claims.

I claim:

1. An actuating linkage for a water closet valve having

a stem, said linkage comprising an elongated operating lever terminating at one end in an operating member, said operating member having a first portion extending longitudinally of said operating lever and a second portion attached to said first portion and extending laterally therefrom and substantially normal thereto, said second portion having an opening therein of a size approximating but larger than the cross-sectional size of said stem so as slidably but snugly to receive said stem, said second portion also being angularly related to the lever and to said first portion in such manner that when said second portion occupies a substantially horizontal position said first portion is inclined to the vertical.

5 15 2. The construction set forth in claim 1 wherein said first portion of said operating member is telescopingly mounted on said lever, and including means reacting between said first portion and said lever for maintaining said member on said lever at any one of a number of selected positions and adjustment.

10 20 3. The construction set forth in claim 2 wherein said operating member is bent intermediate its ends to form said first portion and said second portion.

15 25 4. The construction set forth in claim 3 wherein said first portion comprises a sleeve open at both of its ends.
